SUBMERSIBLE CHAMBER

Edmund S. Martine, Los Angeles, Calif.

Application November 16, 1938, Serial No. 240,841

9 Claims. (Cl. 61—69)

This invention relates to submersible chambers and more particularly to a tank or chamber adapted to hold a number of persons and be submerged a moderate distance below the surface of water, and having windows through which to view the subsurface marine environment for amusement, educational and similar purposes.

An object of the invention is to provide a submersible chamber adapted to hold a number of persons in comfort and safety, and be submerged below the surface of the water, and adapted to be raised and lowered at will.

Another object is to provide a submersible chamber for a number of persons having windows through which to view the marine environment for amusement, educational or scientific purposes.

Another object is to provide a structure of the character described, having safe and simple means of operation and control.

Other objects and advantages will appear and be brought out more fully in the following specification, reference being had to the accompanying drawing, wherein,

Fig. 1 is an elevation view of a structure embodying my invention.

Fig. 2 is a sectional view illustrating one of the control features.

Fig. 3 is a sectional view illustrating another of the control features.

Fig. 4 is a modified form of the structure shown in Fig. 2.

Referring more particularly to the drawing, I show a structural framework 5 supported on suitable foundation members 6, such as the ground or a pier or otherwise, structure 5 being adapted to have a tubular member 7 secured thereto at its upper end and to be suitably anchored in the earth 8 under the water. The structure 5 supports a hoisting mechanism 9 which includes suitable gears, a motor and a pulley wheel 10 around which is adapted to run a cable 11 preferably of stranded steel. The cable 11 is carried around a pulley wheel 12 suitably secured in a recess in a column 17 near the bottom thereof.

The submersible unit embodying my invention comprises a drumlike structure 13 having a cylindrical side wall 14, a top 15 and a bottom 16. The drum 13 is preferably of welded steel construction or the like, and has a central column 17 welded to the top 15 and the bottom 16 adapted to receive the tube 7 on which the drum 13 may be raised and lowered. A pair of small

columns 18 are similarly secured to the top 15 and the bottom 16 and contain the cable 11.

A suitable water-tight door 19 is provided in side wall 14, and an emergency hatch 20 may be provided in the top 15. A number of port holes or windows 21 are provided in side wall 14 through which the occupants of the chamber may view the marine conditions when the tank is submerged.

At a suitable point on the cable 11 is secured a cylinder 22 preferably by the use of a quantity of Babbitt metal 23. The cylinder 22 has a pair of apertures 24 adapted to receive a stud pin 25 of a hand screw 26 suitably threaded at 27 to one of the columns 18. A control lever 28 suitably mounted within the drum 13 controls the electric hoist mechanism 9 preferably using a standard elevator control. The column 17 has a bracket 29 secured thereto and a hand wheel 30 is secured to a screw 31 having a threaded connection with bracket 29, and a brake shoe 32 is swivel mounted on screw 31 and has an arcuate surface for engagement with tube 7.

The operation of the invention should be apparent from the foregoing description. The raising and lowering of the drum 13 is normally done by the operation of the hoisting mechanism 9 controlled by the lever 28, the drum 13 being secured to the cable 11 by the stud 25 and the hand wheel 26.

The buoyancy of the drum 13, however, is great enough so that after submersing, the drum may be raised by this buoyancy in which case the brake 32 is set against the tube 7 and the studs 25 released from the cylinder 22. The brake 32 is used to prevent the drum 13 being violently projected up out of the water by reason of its buoyancy to the injury of the occupants and damage to the structure. It will thus be apparent that in the event of the failure of the hoisting mechanism 9, the drum 13 can be safely released from the cable 11 and brought to the surface. The raising and lowering of the drum 13 on the tube 7 as described, effectively prevents injury to the chamber by reason of the wave activity.

In Fig. 4 is shown optional cable clutch mechanism wherein a shoe member 32 carried by a threaded stud 33 in tubular member 18 is pressed against cable 11 by the action of a hand wheel 34.

Having described my invention what I claim is:

1. A submersible structure as described, comprising a vertical tubular guide anchored in the river bed and above the surface of the water, a drum surrounding the guide and having a well through which the guide passes, a cable secured

to said drum, a pair of pulleys for said cable, an anchoring means for said pulleys above and below the surface of the water, respectively.

2. A submersible structure as described, comprising a vertical tubular guide anchored in the river bed and above the surface of the water, a drum surrounding the guide and having a well through which the guide passes, a cable secured to said drum, a pair of pulleys for said cable, an anchoring means for said pulleys above and below the surface of the water, respectively, said anchoring means including a tubular member, said drum having means for slidable engagement with said tubular member.
3. A submersible structure as described, comprising a vertical tubular guide anchored in the river bed and above the surface of the water, a drum surrounding the guide and having a well through which the guide passes, a cable secured to said drum, a pair of pulleys for said cable, an anchoring means for said pulleys above and below the surface of the water, respectively, said anchoring means including a tubular member, said drum having means for slidable engagement with said tubular member.
4. A submersible structure as described, comprising a drum, a cable secured to said drum, a pair of pulleys for said cable, an anchoring means for said pulleys above and below the surface of the water, respectively, said anchoring means including a tubular member, said drum having means for slidable engagement with said tubular member, said engaging means comprising a second tubular member adapted to receive said first tubular member.
5. A submersible structure as described, comprising a vertical column having its lower end anchored below the surface of a body of water and having its upper end secured above said surface, a drum having a tubular member extending therethrough adapted for slidable engagement with said column, a cable adapted to travel along said column and extending through said drum, a tubular member in said drum for said cable and having engaging means therefor, and a brake secured to said first tubular member.

adapted for engagement with said column, and reversible power means for said cable.

6. A submersible structure as described comprising a vertical tubular guide anchored in the bed of the river and above the surface of the water, a drum surrounding the guide and having a well through which the guide passes, a cable for hoisting and lowering said drum, and a brake operated from within the drum for engaging the guide for controlling the movement of the drum thereon.

7. A submersible structure as described comprising a vertical tubular guide anchored in the bed of the river and above the surface of the water, a drum surrounding the guide and having a well through which the guide freely passes, a cable for raising and lowering the drum and passing through the well in the drum and locked to the drum, means operated within the drum for releasing the same from the cable, and a brake mechanism operated within the drum for engaging the guide and controlling the movement of the drum on the guide.

8. A submersible structure as described comprising a vertical tubular guide anchored in the river bed and above the surface of the water, a drum surrounding the guide and passing through a well therein, an endless cable passing over pulleys carried by the upper and lower ends of the guide and passing through the wells in the drum, means for locking the cable to one of the wells carried by the drum, means for releasing said locking means, and a brake operated from within the drum for engaging the guide and controlling the movement of the drum thereon.

9. A submersible structure as described comprising a vertical tubular guide anchored in the river bed and above the surface of the water, a drum surrounding said guide and having a well through which the same passes, an endless cable passing around pulleys carried by the upper and lower ends of the guide and passing through wells in the drum, means carried by one of the wells for locking the cable thereto, means for releasing said locking means, a brake operated from within the drum for engaging the guide and controlling the movement of the drum on the guide, means for driving the upper pulley, and an electric control within the drum for controlling said driving means.

EDMUND S. MARTINE.
